US00D834651S

(12) **United States Design Patent** (10) Patent No.: **US D834,651 S**
Schultheis et al. (45) Date of Patent: **** Nov. 27, 2018**

(54) **PLAYING SURFACE FOR A SPINNING TOP TOY**

(71) Applicant: **TOMY COMPANY, LTD.**, Tokyo (JP)

(72) Inventors: **Douglas Arthur Schultheis**,
Cumberland, RI (US); **Ramon Antonio Campos**, Pawtucket, RI (US);
Michelino Paolino, Jr., Rumford, RI (US)

(73) Assignee: **TOMY COMPANY, LTD.**, Tokyo (JP)

(**) Term: **15 Years**

(21) Appl. No.: **29/615,378**

(22) Filed: **Aug. 29, 2017**

(51) LOC (11) Cl. **21-01**

(52) U.S. Cl.

USPC **D21/338; D21/397**

CLAIM

The ornamental design for a playing surface for a spinning top toy, as shown.

DESCRIPTION

FIG. 1 is a front view of the playing surface for a spinning top toy showing our design;
FIG. 2 is a left side view thereof;
FIG. 3 is a rear view thereof;
FIG. 4 is a right side view thereof;
FIG. 5 is a top view thereof;
FIG. 6 is a bottom view thereof; and,
FIG. 7 is a perspective view thereof.
